POLISHING WHEEL

Joseph F. Coulter, Birmingham, and Isabell J. Lupu, Lincoln Park, Mich.

Application May 21, 1948, Serial No. 28,328

7 Claims. (Cl. 51—193)

1

This invention generally relates to buffing and polishing wheels and more particularly pertains to a buffing and polishing wheel assembly of exceptionally long-life characteristics comprising a rotatable core, polishing pads, and attaching keys for securing the pads to the core.

The principal object of the invention is to provide attaching keys which are quickly attachable and detachable to the core member for securing the polishing pads to the core member. The keys are first assembled to the pads and then locked in the core thereby securing the pads to the core.

Another object of the invention is to provide means for attaching the polishing pads to the core member so that the pads are quickly and easily attached or detached individually with the operator handling only one pad and key at a time.

Another object of the invention is to provide key-ways and recesses in the core which serve the dual purpose of co-acting with the attaching keys and of providing passages for movement of air under centrifugal force which movement of air ventilates the pads and eliminates whistling or humming.

A further object of the invention is to provide detachable securing means for attaching the pads to the core which are connected to the core at a point interiorly removed from the outer periphery of the core, and substantially within the core body.

A still further object of the invention is to provide a cross-head on the connecting key of such length that the ends of each cross-head are proximate to the respective ends of the cross-heads which lie on either side of same thereby providing a segmental circumference of cross-heads surrounding the outer periphery of the core for the purpose of extending the base portion of the pads circumferentially around the core at its outer periphery to effect a full distribution of the pads at their working surface thereby providing an uninterrupted peripheral working surface on the buffing wheel.

A still further object of the invention is to provide a polishing wheel which may be used in multiple units to furnish an enlarged working surface, which wheels, when placed in side by side relationship not only lock the attaching keys in their respective slots in the cores, but also position the crossheads on the keys in parallel relationship to the circumference of the cores which position fully extends the pads circumferentially of the core.

2

These and other objects will be more readily apparent from the following description, the appended claims, and the attached drawings, in which:

5 Fig. 1 is a side view of a polishing wheel of the invention with several of the pads and keys removed therefrom to better illustrate the various parts of the invention;

10 Fig. 2 is a partial cross-sectional view of Fig. 1 taken on the line 2—2 thereof showing the key attachment more clearly between the pads and the core and the manner of placing several cores in side by side relationship to obtain an enlarged working surface;

15 Fig. 3 is a partial cross-sectional view of Fig. 2 taken on the line 3—3 thereof showing the relation between the core, pads, and keys together with one manner of holding the pads in alignment;

20 Fig. 4 is a cross sectional view of Fig. 3 taken on the line 4—4 thereof illustrating the neck portion of the core key-way;

Fig. 5 is a perspective view of an attaching key illustrating a modification;

Fig. 6 is a perspective view of an attaching key equipped with depending ends on the cross-head thereof for holding the pad in alignment; and

Fig. 7 is a face view of a polishing pad showing the center reinforcing disc and the center aperture therein for receiving the neck portion of the key and the two side apertures for receiving positioning means to keep the pad in alignment.

Referring to the drawings, core member 20, Figs. 1 and 2, is axially mounted on any suitable rotatable shaft 21 which occasions the rotary movement of the core member 20 when powered, and is provided with radially disposed key-ways 22 which lead inwardly from the outer periphery of the core member 20 and terminate interiorly of same in recesses 23, while studs 24 are mounted on the outer periphery of the core member 20.

Key 25 is adapted to lie in the keyway 22 and recess 23 of the core member 20 Figs. 1 to 4 and comprises neck portion 26, locking head 27 and cross-head 28 which may optionally be formed with depending dogs 29, Fig. 6, or an arcuate head, Fig. 5 or both.

Polishing pad 30, Figs. 1, 2, 3 and 7, comprises elliptical or oval shaped portions 31 of fibrous material such as cloth, several layers deep, which portions 31 are secured together in their central area by stitching 32 or other suitable means and reinforcing element 33 may be utilized to strengthen this area by also stitching same to the portions 31. The pad 30 has a central aper-

ture 34 and two off-center apertures 35 which are located on either side of the central aperture 34 and are so positioned that the longest diameter 33 of the pad 30 lies across the centers of the three apertures. In other words, the two side apertures 35 are positioned adjacent the long sides of the oval shaped portions 31 of the pad 30. The pad is preferably oval in shape but may assume any suitable shape.

It can here be pointed out that if a key 25 of the type shown in Fig. 6 is employed equipped with depending dogs 29 for positioning the polishing pad 30 relative to the core member 20, the studs 24 of the core member 20 are deleted from the core member 20; the dogs 29 and studs 24 being optional in the invention.

In assembling the polishing wheel from its component parts, Figs. 1, 2 and 3, the locking head 21 of the key 25 is forced through the central aperture 34 of the pad 30; the apertures 35 of the pad 30 are located over the studs 24 on the core member 20; the locking head 21 of the key 25 is run through the key-way 22 in the core 20 until it lies in the area of the recess 23; the cross head 28 is then turned to lie in a plane parallel to the periphery of the core 20. This turning of the cross-head 28 rotates the neck portion 25 and the locking-head 21 connected thereto so that locking-head 21 lies within the recess 23 at right angles to the key-way 22 thereby securing the key 25 and pad 30 to the core 20.

The placing of the apertures 35 of the pad 30 over the studs 24 of the core member 20 locates the long dimension of the pad 30 parallel to the circumference of peripheral edge of the core member 20 and, as the cross-head 28 on the key 25 is also parallel to the peripheral edge of the core member 20, the long dimension of the pad 30 is extended circumferentially of the core member 20 by the length of the cross-head 28 on the key 25 while the short dimension of the pad 30 is free to fold without extension around the sides of the cross-head 28, Figs. 1, 2, and 3.

The cross-head 28 may be equipped with dogs 29, Fig. 6, and when this type of key is used the studs 24 are not used on the core 20. The dogs 29 are inserted into the side apertures 35 of the pad 30 when the key 25 is first inserted in the pad 30 via its locking head 21 and neck portion 25. The locking-head 21 is then run through the key-way 22 of the core member 20 until it lies in the area of the recess 23. The key is then turned so that its cross-head 28 lies parallel to the circumference of the core member 20, and this causes the pad 30 to turn and be positioned by the dogs 29 with long dimension of the pad parallel to the circumference of the core member 20 thereby correctly positioning the pad 30 on the core member 20. This turning action also locks the key 25 in the core member 20 thereby attaching the pad to the core.

Optionally, the cross-head 28 may be curved to conform to the circumference of the core member 20 as seen in Fig. 5, and, the ends of the cross-head may be extended beyond the dogs 29 of Fig. 6 as desired, depending on the size of the core member 20 and the number of pads 30 disposed thereon.

To set up a polishing wheel unit using the invention, several polishing wheels are assembled from the component parts, placed in side by side relationship as seen in Fig. 2 on a rotatable shaft, such as the shaft 21, and secured thereon by nuts or other fastening means. In usual usage, several wheels are generally employed, and their number generally runs from about 4 to 20 and

even as high as 50 at one time on the same rotatable shaft. When the wheels are pressed side-wise together on the shaft by the securing means, the cross-heads 28 on the keys 25 are held in parallel position to the circumference of the core members 20 by the fibrous material 31 which forms the pads 30 as the pads 30 fold around the cross-heads 28. This not only insures that the cross-head 28 extends the long dimension of the pad 30 around the circumference of the core member 20, but also, at the same time, positions the locking-head 21 within the recess 23 cross-wise or in locking engagement with the key-way 22. In other words, when the wheels are placed on the shaft, all the individual parts and the complete assemblies are locked up and properly positioned by merely tightening the means which secures the wheels on the rotatable shaft.

When the device is in operation and the rotatable shaft is turning at high speed, the pads 30 are subjected to great centrifugal force and they are urged radially outward from the center of the shaft's rotation and assume a shape and position similar to the position and configuration of the pads 30 in Figs. 1 and 2 which results in a circular working surface which is peripherally continuous and uninterrupted. It will be noted that this is effected by the extension of the long dimension of the pads 30 by the cross heads 28 on the keys 25, as the cross heads 28 lie substantially end to end around the circumference of the core member 20 thus spreading the pads on a substantially complete circumference at the periphery of the core member 20 from which circumference they are thrown radially outwardly by centrifugal force to form a substantially complete circumference at the working surface 40 of the polishing wheel.

As the pads are preferably oblong or oval in shape and only partially extended by the cross head circumferentially, the straight lines of centrifugal force cause the pads 30 to overlap themselves or "ruffle up" in their remaining area especially adjacent their outer working surface 40 which provides a rough and durable surface to absorb polishing material and to do a polishing job.

When the polishing wheel assembly is rotating rapidly as seen in Fig. 2, fluid air enters the recesses 23 as indicated by the arrows and this air is thrown radially outwardly via the key-way 22 in the cores 20 and between the pads 30 attached thereon. This provides a cooling medium at the working surface 40 of the polishing wheels and the circulation of fluid air also eliminates humming and whistling.

In the event that it is desired to use only one polishing wheel, side plates may be set on either side of the core to lock the various parts in position. Also, the polishing pads may be positionable by riveting or otherwise securing them to the key. This and many other additions, deletions, changes, and modifications can be made in the disclosed device without departing from the spirit of the invention which is limited only by the scope of the appended claims.

We claim:

1. A polishing wheel comprising an annular core member, oblong polishing pads having a centrally located aperture and off-center apertures located on the long axis thereof, keys detachably attaching said polishing pads to said core member via the centrally located aperture of said pads, and means adapted to cooperate with the off-center aperture of said pads to position

the long dimension of said pads parallel with the circumference of said core member, and arcuate cross-heads on said keys lying substantially in end to end relationship parallel to said core extending the long dimension of said pads at said core thus spreading said pads on a complete circumference at the periphery of said core from which circumference said pads are thrown radially outwardly by centrifugal force to form a complete circumference at the working surface of the polishing wheel.

2. A buffing wheel of the type comprising a discular chuck adapted for rotation, a plurality of buffs and a plurality of key elements having bow, stem and bit portions for releasably engaging said buffs and chuck to removably mount the buffs on said chuck and characterized in that said chuck has a plurality of passageways extending radially from the discular periphery of said chuck; each of said passageways having a terminal chamber portion intermediate the discular periphery and axis of rotation of said chuck and parallel extending and laterally communicating eye and slot keyway portions in axial communication with said terminal chamber portion and of cross-sectional dimensions and contour approximating those of the key element stem and bit portions, said keyway portions being adapted for guiding said key element stem and bit portions inwardly of the discular periphery of said chuck to locate the bit portion of said key element in the terminal chamber portion of said passageway; said terminal chamber portion having a surface extending parallel to a sector of the discular periphery of the chuck and adapted for engagement by the key element bit portion located in said terminal chamber upon rotation of the key element from an angular relation in which the stem and bit portions thereof register with said keyway eye and slot portions of the passageway whereby the key element will be restrained against movement relative to the chuck.

3. A buffing wheel of the type comprising a discular chuck adapted for rotation, a plurality of buffs and a plurality of key elements having bow, stem and bit portions for releasably engaging said buffs and chuck to removably mount the buffs on said chuck and characterized in that said chuck has a plurality of passageways extending radially from the discular periphery of said chuck, each of said passageways having a terminal chamber portion intermediate the discular periphery and axis of rotation of said chuck and parallel extending and laterally communicating eye and slot keyway portions in axial communication with said terminal chamber portion and of cross-sectional dimensions and contour approximating those of the key element stem and bit portions, said keyway portions being adapted for guiding said key element stem and bit portions inwardly of the discular periphery of said chuck to locate the bit portion of said key element in the terminal chamber portion of said passageway; said terminal chamber portion having a surface extending parallel to a sector of the discular periphery of the chuck and adapted for engagement by the key element bit portion located in said terminal chamber upon rotation of the key element from an angular relation in which the stem and bit portions thereof register with said keyway eye and slot portions of the passageway whereby the key element will be restrained against movement relative to the chuck, a plurality of studs extending radially from the discular periphery of said chuck, each

stud being located on one side of and in spaced proximity to one of said passageways and adapted to be engaged by the bow portion of the key element whereby said key element bow and stem portions form with the engaged stud a confined space on the discular periphery of the chuck for containing a portion of one of said buffs.

4. A buffing wheel of the type comprising a discular chuck adapted for rotation, a plurality of buffs and a plurality of key elements having bow, stem and bit portions for releasably engaging said buffs and chuck to removably mount the buffs on said chuck and characterized in that said chuck has a plurality of passageways extending radially from the discular periphery of said chuck; each of said passageways having a terminal chamber portion intermediate the discular periphery and axis of rotation of said chuck and parallel extending and laterally communicating eye and slot keyway portions in axial communication with said terminal chamber portion and of cross-sectional dimensions and contour approximating those of the key element stem and bit portions, said keyway portions being adapted for guiding said key element stem and bit portions inwardly of the discular periphery of said chuck to locate the bit portion of said key element in the terminal chamber portion of said passageway; said terminal chamber portion having a surface extending parallel to a sector of the discular periphery of the chuck and adapted for engagement by the key element bit portion located in said terminal chamber upon rotation of the key element from an angular relation in which the stem and bit portions thereof register with said keyway eye and slot portions of the passageway thereby the key element will be restrained against movement relative to the chuck, each of said studs has a surface spaced a radial distance equal to the distance between the bow and bit portions of one of said key elements from the plane of said terminal chamber portion's surface of the passageway with which said stud is associated as aforesaid, said stud surface being adapted to be engaged by said bow portions of the key element whereby the key element will be held against radial movement relative to the chuck when the bow portion engages said stud surface and the bit portion engages said terminal chamber portion's surface.

5. A buffing wheel of the type comprising a discular chuck adapted for rotation, a plurality of buffs and a plurality of key elements having bow, stem and bit portions for releasably engaging said buffs and chuck to removably mount the buffs on said chuck and characterized in that said chuck has a plurality of passageways extending radially from the discular periphery of said chuck; each of said passageways having a terminal chamber portion intermediate the discular periphery and axis of rotation of said chuck and parallel extending and laterally communicating eye and slot keyway portions in axial communication with said terminal chamber portion and of cross-sectional dimensions and contour approximating those of the key element stem and bit portions, said keyway portions being adapted for guiding said key element stem and bit portions inwardly of the discular periphery of said chuck to locate the bit portion of said key element in the terminal chamber portion of said passageway; said terminal chamber portion having a surface extending parallel to a sector of the discular periphery of the chuck and adapted for engagement by the key element bit portion located

in said terminal chamber upon rotation of the key element from an angular relation in which the stem and bit portions thereof register with said keyway eye and slot portions of the passage-way whereby the key element will be restrained against movement relative to the chuck, each of said buffs has an opening of dimensions and contour approximating the cross-sectional dimensions and contour of one of said studs and adapted to receive said stud therein whereby 10 said buff may be impinged on said stud and prevented from movement relative to the chuck when the key element's bow portion engages said stud.

6. A polishing wheel comprising an annular core including means for releasable locking pad attaching keys thereto, oblong polishing pads each having a centrally located aperture and at least one side aperture disposed on the axis of the long dimension of said pad, keys adapted to coact with said means disposed in the central 20 apertures of said pads, heads on said keys adapted to spread said pads relative to the circumferential periphery of said core, and studs on said core positioned in the side apertures of said pads fixing the long dimension of said pads relative to 25 said heads and said core.

7. A polishing wheel comprising an annular core including means for releasable locking pad attaching keys thereto, oblong polishing pads each having a centrally located aperture and at least one side aperture disposed on the axis of the long dimension of said pad, keys adapted to coact with said means disposed in the central apertures of said pads, heads on said keys adapted to spread said pads relative to the circumferential periphery of said core, and dogs on said heads positioned in the side apertures of said pads fixing the long dimension of said pads relative to said heads and said core.
